UNITED STATES PATENT OFFICE.

ENOS C. VERKLER, OF CHICAGO, ILLINOIS

GARMENT-HANGER.

1,204,619.

Specification of Letters Patent. Patented Nov. 14, 1916.

Application filed April 23, 1915. Serial No. 23,380.

To all whom it may concern:

Be it known that I, ENOS C. VERKLER, a citizen of the United States, and a resident of the city of Chicago, county of Cook, and 5 State of Illinois, have invented certain new and useful Improvements in Garment Hangers, of which the following is a specification.

My invention relates to improvements in garment hangers, and has for its object the production of a device of this character of the type wherein is provided means for effectually locking the garment thereto.

A further object is the production of a 15 garment hanger which will be extremely simple in construction and efficient in use.

Other objects will appear hereinafter.

The invention consists in the combinations and arrangements of parts hereinafter 20 described and claimed.

The invention will be best understood by reference to the accompanying drawing forming a part of this specification, and in which,

25 Figure 1 is a partially sectional side elevation of a garment hanger embodying the invention, and Fig. 2 is a top plan view thereof.

The preferred form of construction, as 30 illustrated in the drawing, comprises an elongated bowed or curved body 1 formed of wood. The body 1 is provided midway its ends with the usual upwardly extending suspending hook 2.

35 Coöoperating with the body 1 at either side of the suspending hook 2 is a clamping device formed of a substantially U-shaped spring wire 3. One end 4 of the wire 3 is driven into the body 1 at the under side

40 thereof, said end 4 entering said body at an angle in order to securely lock the same thereto and thereby prevent ready withdrawal of the same. The opposite end of the wire 3 extends loosely through an elongated vertically extending slot 5 provided 45 in the member 1, the upper terminal of said end being bent outwardly as at 6 to constitute a jaw adapted to yieldingly engage against the upper side of the body 1. The 50 arrangement is such, as will be seen, that

the end portion 6 may be moved upwardly by engagement with the bight portion of the member 3 and pressing the same upwardly. When this is done, the member 3 will be flexed or sprung out of its normal 55 shape so that when released the end portion 6 will be immediately returned to its initial position. In order to prevent bending instead of flexing of the member 3 and thereby "kill" the resiliency of the same, the 60 member 3 adjacent the anchored end 4 thereof is formed with a wide curve 7. Through this formation the flexing or springing of the member 3 adjacent the pivot or fulcrum thereof is distributed over a considerable 65 length and thus the burden correspondingly distributed and over taxation at any one point in the wire obviated.

In use the edges of the garment arranged upon the hanger are clamped between the 70 ends 6 and the upper sides of the body 1, with the result that accidental slipping of the garment from the hanger is positively prevented. In order to prevent injury to the garment through rusting of the wire, 75 and in order to prevent slipping from engagement with the ends 6 of the wire members, said ends are preferably covered with tubular rubber coverings 8 which are held in position by friction.

While I have illustrated and described the preferred form of construction for carrying 80 my invention into effect, this is capable of variation and modification without departing from the spirit of the invention. 85 I, therefore, do not wish to be limited to the precise details of construction set forth, but desire to avail myself of such variations and modifications as come within the scope of the appended claim.

Having described my invention what I claim as new and desire to secure by Letters Patent is:

A garment hanger comprising an elongated body; and clamping means provided 95 at each end of said body, said means comprising an elongated resilient member having one end secured to said body at the under side thereof and having its opposite end yieldingly engaging against the upper side 100

of said body, the central portion of said member projecting below the under side of said body for manual engagement in pressing the same upwardly to move the last mentioned end of said member from engagement with the upper surface of said hanger body, substantially as described.

In testimony whereof I have signed my name to this specification in the presence of two subscribing witnesses.

ENOS C. VERKLER.
